TAPERED DRAWN STRUCTURAL ELEMENT

Filed July 12, 1926

UNITED STATES PATENT OFFICE.

GEORGE E. BARNHART, OF PASADENA, CALIFORNIA.

TAPERED DRAWN STRUCTURAL ELEMENT.

Application filed July 12, 1926. Serial No. 121,781.

My present invention relates particularly to tubular units designed for use in an up-standing or projecting position, as for the support of loads or the resistance or application of pressures; and it is a particular object of my invention to provide for the production, at small cost and by operations which are favorable to the production of so-called "fiber" therein, of masts, posts, levers, beams and the like, in which the distribution of metal and "fiber" is favorable to a maximum strength in proportion to the weight thereof.

Posts, beams, and the like, have heretofore been formed from cast, drawn or rolled stock; but the cross sections of units provided for the indicated uses have commonly been uniform throughout the length thereof.

In published calculations and formulas relating to metallic masts, beams, and the like, for the support of particular loads, a uniformity of cross section or a "stepped" construction has commonly been assumed,—doubtless for the reason, among others, that the quantity production of drawn tapered elements, in a manner favorable to a desired uniform or non-uniform distribution of metal therein, has appeared impracticable; but, as set forth in my recent application Serial No. 101,656, filed April 13, 1926, "method of drawing elongated metal articles", I have devised practical means for the production of tapered drawn tubular shapes; and it is to the protection of certain especially advantageous shapes, obtainable by the means and methods set forth in my mentioned application, or by equivalent means, that the present application is primarily directed.

It is an object of this invention to provide hollow structural units comprising sections or parts which are longitudinally tapered and in which the thickness of a metallic wall, at various levels, may vary, according to the intended uses, in relation to the diameter or radius thereof,—the proportion of "fiber" to cross sectional area being, however, greatest in the constricted portions thereof.

Other objects of my invention, including the adaptation of posts, masts, or the like, to carry cross arms and/or circular members, and including the optional provision of drawn base members or units for use in conjunction with masts or posts of the described character, or of any preferred char-

acter,—such base members or units being optionally tapered but provided with walls which are thickest in the regions of their least diameter, and including also the provision of cantilever or other beams or members having a non-circular outline, and/or the provision of stocks suitable for use in the production of tapered levers or other machine parts, may be best appreciated from the following description of alternative embodiments of my invention taken in connection with the appended claims and the accompanying drawings, in which

Fig. 1 may be regarded as a vertical section through a mast or post organization comprising a main tubular unit and a base unit,—both units being formed by drawing a tubular stock in such manner as to produce a maximum proportion of fiber in the narrowest regions thereof.

Figs. 2, 3 and 4 may be regarded respectively as cross sections in the planes indicated by the lines 2—2, 3—3 and 4—4 of Fig. 1, the ratio of fiber to cross sectional area therein being diagrammatically suggested by the use of X's.

Fig. 5 illustrates a portion of a post within the scope of my invention, but disclosing walls which, though tapered, are of uniform thickness.

Fig. 6 may be regarded as a vertical section through a lever, such as a gear shift lever, formed from a tubular unit illustrative of my invention, but bent and provided with terminal members immaterial to my invention.

Fig. 7 is a diagrammatic view of a cantilever beam illustrating an embodiment of my invention in which a tubular element is provided with a non-circular outline and with non-uniform walls.

Fig. 8 may be regarded as a vertical section, taken as indicated by the line 8—8 of Fig. 7.

Fig. 9 is a view showing, on an enlarged scale, an optional cross sectional outline of a part of, for example, the lever illustrated in Fig. 6.

It has heretofore been possible to provide tapered posts of the general form illustrated in Fig. 5 by casting or by the elaboration of sheet metal; but it is possible to provide tubular units of this form by drawing operations such as are described in my mentioned application; and a great advantage

of the drawn products, as compared with cast products or products formed from sheet metal, lies in the longitudinal arrangement and concentration of so-called "fiber",—
 5 which results from the drawing operation; and, although I may provide drawn units 10 either with uniform walls 11, or with walls which diminish in thickness in the direction of diminishing outside diameter
 10 or with walls which increase in thickness in the direction of diminishing diameter, for most purposes I prefer to maintain a substantially constant ratio of metallic wall to diameter, substantially as indicated in Figs.
 15 1-4 inclusive.

Referring to the details of that specific embodiment of my invention illustrated in Figs. 1-4 inclusive, the tubular unit 12 is shown as upwardly tapering, except as it
 20 is interrupted by an expansion 13 (suitable for the support of a cross arm 14, or the like) and by a constriction 15 (suitable for the support of a split or other ring 16, as for the attachment of an insulator, a guy
 25 wire, a pulley, or the like) at a substantially uniform rate.

In order to adapt a post or mast or other unit of the general character described for alternative uses, optionally leaving a lower
 30 or intermediate portion thereof, as the portion 17, in its "original" state, (the comparatively thick walls in the region referred to being adapted to resist corrosion, in case the unit is to be inserted in the ground) I may
 35 optionally provide the same with additional enlargements or constrictions, as the constriction shown at 18, to provide for a split or other ring 19 (adapted to carry a pulley, or the like, not shown); and, if desired, the
 40 unit may be downwardly tapered, in a manner suitable to its use alternatively in direct contact with the soil, or in conjunction with a base member or unit 20,—the latter being shown as provided not only with a downwardly expanded portion 21, but with a short upwardly expanded portion 22, adapted to cooperate with a downwardly tapered portion 23 of the said unit 12.

When units 12 are set directly in the
 50 ground, whether by tamping within a hole or by driving, or otherwise, a thickest wall portion, such as the mentioned widest part 17 (presumably representing the original stock) may be disposed at the ground
 55 level,—any excess metal at this point being utilized in the withstanding of corrosion and/or resistance to any shearing or other local force; and the harmonious and/or outward taper of a mast or beam constructed
 60 in the general manner suggested is then entirely suitable to the support of a uniformly distributed load, or to the resistance of unilateral pressures such as those produced by a relative movement of air or water—both
 65 the distribution of metal and the character

of the metal, including longitudinal "fiber" (concentrated in the general manner suggested by the diagrammatic showing of X's in Figs. 2, 3 and 4) being especially favorable; but, although the unit 12 is shown as 70 provided with upwardly tapered ends, it is not always desirable that a lower section 23 be provided, or that, when provided, the walls of such a lower section shall diminish in thickness in the manner illustrated in 75 Figs. 2, 3 and 4. For example, the wall 24 of the lower section 23 of a unit 12 may be kept practically uniform in thickness, even though this section be tapered, in order the better to adapt the same to a considerable 80 variety of alternative uses.

Even when a unit 12 (assumed to be completed by drawing operations executed with requisite variations in rate of relative movement and in pressure, and otherwise as described in my mentioned copending application, or in any other manner suitable to the results herein described) is intended to have its lower section 23 disposed below ground level, I may associate therewith, as indicated, a base unit such as the unit 20,—shown as having its walls thickest in an intermediate region 25, of maximum constriction,—a tapered seat 26, above the level 25 being provided by the upper section 22 of 95 the unit 20, and adapted exactly or approximately to interfit with a correspondingly tapered section 23 of the unit 12.

The outwardly flared walls of the lower section 21 of the unit 20 may downwardly 100 diminish in thickness as they expand within the soil or within any mass in which the unit 20 may be embedded; but I may nevertheless qualify the sections 20 for various uses,—adapting them, for example, to serve 105 either as bells, embedded in the indicated manner (the downward diminution in the thickness of the walls being then entirely appropriate) or to serve alternatively as exposed base members, suitable to be directly 110 or indirectly attached to a deck, pavement, or the like,—as by means comprising an interfitting plate 27 and a centering or anchoring plate 28. The plates 27 and 28 are shown as respectively engaging section 21 of the 115 base unit 20 and section 23 of the mast unit 12, and as being held to a foundation and in adjusted relationship to one another by means of bolts 19, carrying nuts 30.

For the purpose of providing access to 120 nuts 30, or for the insertion of any desired filling, or for the disposition of instruments and/or connections and/or fittings of any desired character within a bell or base member of the general character described 125 (a cylindrical portion 30^a, at the lower end of the downwardly flared walls 21 being indicative of the character of the stock from which the unit 20 is formed, in case the same is produced by my mentioned process) any 130

desired openings may be provided in any of the mentioned units,—an opening in the section 21 being shown as provided with a threaded plug 30, and the unit 12 being provided at 31 and 32 with openings suitable for use in wiring.

As shown in connection with the last-mentioned openings, the walls 33 through which they are cut may be suitably thickened to 10 obviate a weakening of the same below a proportionate strength characterizing all parts of the unit or characterizing an organization formed by the conjoint use of a plurality of units; and, if desired, any of my 15 units may be provided with threads (preferably formed by pressing, or by another operation involving no removal of metal)—a thread at the top of the illustrated post or mast being optionally used for the attachment 20 of a weather-excluding cap 34, and a coarser thread 35, at the opposite (bottom) end being shown as engaging a corresponding thread in a boss 35' upon the centering or anchoring plate 28. It will be obvious 25 that the unit 12 and plate 28 might be used without unit 20; and that by suitably adjusting the plate 28 relatively to the plate 27, and suitably rotating the unit 12, the latter may be brought to a vertical position 30 notwithstanding a slight inclination of the plate 27,—any necessary wedges or washers (not shown) being interposed between the plates 27 and 28.

In Fig. 6 I suggest the use of a structural unit 37, whose walls diminish in thickness consistently with the taper thereof,—fiber being naturally concentrated in the narrow portion 38 thereof, to which a knob 39 may be secured in any preferred way; 40 and, assuming that the unit 37 is to be used as a gear shift lever of that type in which a bend is provided, the change in direction indicated at 40 may be effected either during a drawing operation or subsequently thereto, 45 in a known manner.

In the case of a cantilever beam, supported at one end only, such as the beam 41 of Figs. 7 and 8, the desirable rate of increase in diameter and/or in wall thickness being obviously dependent upon the material used 50 and the distribution of the load, I may, for example, prefer a triangular cross section,—giving to a web 42 on the upper or tension side thereof a thickness substantially less than that of downwardly convergent side walls 43, 43'; and any planks or other units 55 of a supported platform, or the like, may be secured in a suitable way, as by means of counter-sunk screws 44. Depending upon 60 the materials and conditions of use, the inner end of the beam 41, or its equivalent, may be plugged or filled, as at 45, in a manner adapting it to withstand compressive or 65 shearing stresses when built into any wall, as a masonry wall 46, or otherwise secured.

Data regarding the properties of homogeneous beams (including formulas pertinent to moment of inertia, to sectional modulus, to radius of gyration, and also bending-moment formulas and deflection formulas, and comparisons of the properties of cast and drawn structural units respectively assumed to be homogeneous, may be so readily found that I make no effort to include the same, even for purposes of comparison,—an essential fact being that, by reason of the mentioned concentration of "fiber" in the constricted portions of my structural units, the published formulas are by no means adequately descriptive thereof,—one marked effect of the mentioned concentration of "fiber" being a notable relative increase in the toughness or strength thereof relatively to the cross sectional area of constricted portions thereof; but I may mention, in conclusion, that the drawing operations referred to are entirely suitable for use not only upon steel tubes, but upon a great variety of other metallic tubes, including aluminum, nickel, brass or alloy tubes; 90 and that, although the resultant distribution of metal depends, as set forth in my mentioned copending application, upon pressures applied and rates of relative movement, the mentioned operations need 95 involve no application or but little application of artificial heat.

As to the field of usefulness of my novel units, quoting from a discussion contained in the "Elements of Machine Work", copyrighted in 1910 by Robert H. Smith of the Massachusetts Institute of Technology, I call attention to the fact that structural units within the terms of the present specification possess very substantial advantages 100 over the "stepped" diameter structural units heretofore used for trolley posts, and the like, and even more notable advantages, for most uses, over uniform-diameter drawn tubes which are referred to on page 114 of 110 the mentioned publication in the following language:

"They have a wide use in manufacturing and engineering, in automobile axles, running gears, cylindrical and tubular ball and 115 roller bearings, steering rods, tubular spokes and hubs, boiler tubes, bicycle frames and forks, handle bars, saddle posts, pumps, sulkiies, hydraulic and pneumatic tubes, rings in ring spinning and twisting frames, 120 spindles, rolls, bolsters, shafting, piston rods, piston chucks, bushings, sleeves, die-stock handles, pneumatic tools, washers, printing-press rolls, agricultural harvesting and ice machinery, laundry mangle rolls, 125 mandrels for rubber tires and hose, cream separator bowls, frames of surgical operating tables, dental engines, instrument cases, bookcases, chairs, tables, fishing and umbrella rods, canes, display frames, magazine 130

rifles, air guns, toy pistols, masts, signal and trolley poles and flagstaffs, hand railings, etc.

5 "They are obtained in three anneals,— hard, stiff (cannot be bent); medium, tough (can be bent slightly); soft, ductile and pliable (suitable for bending or forming into special shapes).

10 "Small machine parts can be readily made by using tubing slightly over-size, then grinding or machining to size. The parts may or may not be case-hardened. Joints are made by brazing, threading, flanging, expanding, beading, and by shrink, force, 15 drive, sliding, or push fits."

Sign posts, mail box supports and lamp supports (as well as automobile body members and many additional items) might naturally have been included within the 20 above somewhat random enumeration, in view of the fact that uniform seamless drawn tubes up to twenty inches in diameter are said to have been on the market for many years; but the omission of mention of airplane longérons, wing frame members and/or struts, and also the omission of mention of especially rugged and weight-economizing masts required by submarines (these being among the uses to which my structural units are very advantageously applicable) may doubtless be attributed to the 25 recentness of the notable advances made in aerial and submarine navigation.

Although I have herein described several 30 alternative embodiments of my invention, it should be understood not only that various features thereof might be independently employed, but also that numerous modifications additional to those suggested, might 35 easily be devised by those skilled in the art to which this case relates, without involving the slightest departure from the spirit and scope of my invention, as the same is indicated above and in the following claims.

40 The term "drawing" is herein used to include not only operations of the type heretofore commonly so called but also such com-

binations of rolling and drawing as are described in my mentioned application, these combination operations being applicable as 50 well to high carbon steels. I have found that some of my results are obtainable even by rolling, without drawing; but one of the important results of my preferred mode of production which includes drawing is the 55 mentioned increase in longitudinal fiber,— this effect being so notable as to improve the resistance of some of my structural elements to transverse bending strains by 50% or more (tensile strength and compressive 60 strength being also increased, parallel to the grain) as compared with elements of identical weight produced (in case they can be so produced) by mere swaging; and such as to render the products of my process generally 65 identifiable by the fact that, when crushed by lateral pressure, fracture may occur exclusively, or almost exclusively, along longitudinal lines, parallel or approximately parallel to the grain or fiber.

70 I claim as my invention:

1. In means of the general character described, a seamless drawn and tapered tubular structural unit comprising a section which tapers both internally and externally 75 and in which the thickness of wall increases in the direction of diminishing diameter.

2. In means of the general character described: a seamless drawn and tapered tubular structural unit which varies in diameter and whose walls are thickest in a region 80 where the outside diameter is least.

3. In means of the general character described: a seamless drawn and tapered tubular structural unit which varies in diameter, and whose walls are thickest in a region 85 where the outside diameter is least, said unit expanding in opposite directions from said region.

In testimony whereof, I have hereunto set 90 my hand at Los Angeles, California, this 1st day of July, 1926.

GEORGE E. BARNHART.

CERTIFICATE OF CORRECTION.

Patent No. 1,711,824.

Granted May 7, 1929, to

GEORGE E. BARNHART.

It is hereby certified that error appears in the printed specification of the above numbered patent requiring correction as follows: Page 1, line 30, for "No. 101,656" read "No. 101,651"; and that the said Letters Patent should be read with this correction therein that the same may conform to the record of the case in the Patent Office.

Signed and sealed this 2nd day of July, A. D. 1929.
